US00D823020S

(12) United States Design Patent (10) Patent No.: US D823,020 S
(45) Date of Patent: * Jul. 17, 2018

(54) SEATING DEVICE

(71) Applicant: Medline Industries, Inc., Mundelein, IL (US)

(72) Inventors: Michael Paterson, Chicago, IL (US); Matt Costello, Chicago, IL (US); Kristian Trendafilov, Mettmann (DE); Luke Westra, Chicago, IL (US)

(73) Assignee: Medline Industries, Inc., Northfield, IL (US)

() Term: 15 Years

(21) Appl. No.: 29/570,679

(22) Filed: Jul. 11, 2016

Related U.S. Application Data

(63) Continuation-in-part of application No. 29/558,299, filed on Mar. 16, 2016, which is a continuation of application No. 14/845,235, filed on Sep. 3, 2015.

(57) CLAIM

The ornamental design for a seating device, as shown and described.

DESCRIPTION

FIG. 1 is a front elevation view of a seating device showing our new design;

FIG. 2 is a rear elevation view thereof;

FIG. 3 is a left elevation view thereof;

FIG. 4 is a right elevation view thereof;

FIG. 5 is a top plan view thereof;

FIG. 6 is a bottom plan view thereof; and,

FIG. 7 is a perspective view thereof.

All broken lines, including the dash-dot lines above, are included for the purpose of illustrating use and environment and form no part of the claimed design.

1 Claim, 4 Drawing Sheets
